(57) CLAIM

I claim the ornamental design for a cap, as shown and described.

DESCRIPTION

FIG. 1 is a top perspective view of my new design for a cap;

FIG. 2 is a front view thereof;

FIG. 3 is a side view thereof;

FIG. 4 is a rear view thereof;

FIG. 5 is another side view thereof;

FIG. 6 is a top view thereof;

FIG. 7 is a bottom view thereof;

FIG. 8 is a bottom perspective view thereof;

FIG. 9 is a top perspective view of another embodiment of my new design for a cap;

FIG. 10 is a rear view thereof;

FIG. 11 is a side view thereof;

FIG. 12 is a front view thereof;

FIG. 13 is another side view thereof;

FIG. 14 is a top view thereof;

FIG. 15 is a bottom view thereof; and,

FIG. 16 is a bottom perspective view thereof.

The broken lines are shown for the purpose of illustrating environmental subject matter and form no part of the claimed design.

1 Claim, 10 Drawing Sheets
